UNITED STATES PATENT OFFICE.

GEORGE W. OGLE, OF MORGAN PARK, ILLINOIS.

BREECH-LOADING FIRE-CRACKER PISTOL.

SPECIFICATION forming part of Letters Patent No. 427,356, dated May 6, 1890.

Application filed December 31, 1889. Serial No. 335,523. (No model.)

To all whom it may concern:

Be it known that I, GEORGE WASHINGTON OGLE, of Morgan Park, in the county of Cook and State of Illinois, have invented a new 5 and useful Breech-Loading Fire-Cracker Pistol, of which the following is a full, clear, and exact description.

The object of my invention is to produce a cheap, simple, and safe toy pistol, wherein 10 fire-crackers may be utilized as ammunition to project a light harmless missile; and it consists in the peculiar construction of the device, as is hereinafter described and claimed.

Reference is to be had to the accompanying 15 drawings, forming a part of this specification, in which similar letters of reference indicate corresponding parts in all the figures.

Figure 1 is a plan view of the device. Fig. 2 is a side elevation of the same; and Fig. 3 is 20 a vertical longitudinal section taken through the axial center, as indicated by the line 3-3 in Fig. 1.

The pistol-stock A and barrel B are preferably made integral of wood or cast from 25 metal, and are shaped, substantially as shown, to imitate a breech-loading pistol, there being projections *a* and *b* formed near the grip-piece of the handle, which respectively represent the hammer and trimmer of a real fire- 30 arm, and a sight-piece *b'*, also in the usual place on the barrel B. From the muzzle end *c* of the barrel B to the point *c'* the barrel is axially perforated, the caliber of said bore being considerably larger than a fire-cracker 35 of ordinary size.

At *c'* an upwardly and rearwardly curved aperture is formed in the portion that substantially corresponds to the breech-block of a pistol, which aperture from its direction 40 affords an elongated inlet *c*² above at the rear end of the barrel B, into which the fire-cracker C may be readily introduced and slid forward until it is fully within and in contact with the rear end of the barrel, where a vertical 45 shoulder is formed, the fuse *d* of the cracker being held to project outside of the loading-orifice *c*².

In operation the fire-cracker is introduced

as represented in Fig. 3, and a missile D, of cork, gum, or other similar material, is inserted 50 in the muzzle of the barrel B, said plug D fitting tightly therein. The fuse being lighted, the pistol may be sighted, and the explosion of the fire-cracker will drive the missile D from the barrel with considerable force to- 55 ward the object aimed at.

Some of the gas resulting from detonation of the fire-cracker will escape rearwardly; but there will be no fire or any portion of fire-cracker material so projected, all passing out 60 of the muzzle, as is usual with real fire-arms.

The device is made sufficiently substantial to avoid liability of fracture, and the windage afforded around the cracker-body and the escape provided at the rear end for a portion 65 of the gases of explosion obviate any contingency of accidental rupture of the barrel and injury to the hand of the operator.

Owing to the noise and fire as well as smoke produced by the fire-cracker ammunition, 70 which simulates the operation of discharging a real pistol, the device affords harmless amusement to youth and supplies a substitute for more dangerous toys of the same genus.

Having thus fully described my invention, 75 what I claim as new, and desire to secure by Letters Patent, is—

1. A toy pistol having its barrel and stock constructed of one piece of material, the bore of the barrel communicating at its rear with 80 an upwardly and outwardly extending loading-aperture of less diameter than said bore, substantially as shown and described.

2. A toy pistol having its barrel and stock constructed of one piece of material, on which 85 are formed simulations of a sight-piece, trigger, and hammer, the bore of the barrel communicating at its rear with an upwardly and outwardly curved loading-aperture of less diameter than said bore, substantially as 90 shown and described.

GEORGE W. OGLE.
